AUTOMATIC CRATING MACHINE

Charles Alvin Miller, Sr., Bainbridge, Ga.

Application May 11, 1935, Serial No. 21,021

1 Claim. (Cl. 226—14)

This invention relates to crating machines in general; and, more particularly to a novel machine for automatically assembling bottles, or other containers, and automatically placing them in proper order in shipping crates or the like.

The main object of the present invention is to provide a simple and effective apparatus which may be used conveniently and advantageously in conjunction with the machinery commonly employed in bottling plants, whereby the containers or bottles may be automatically placed in the crates without danger of breaking or disorder.

A further object of the invention is to provide apparatus of the character referred to with safety mechanism to prevent the movement of crates through the machine whenever the feed of bottles or the like is stopped.

Other objects of the invention will become apparent as the detailed description thereof proceeds.

In the drawings:

Figure 1 is a side elevation of the apparatus embodying the present invention;

Figure 2 is a top plan view of the apparatus shown in Figure 1;

Figure 3 is a vertical transverse section taken on the line 3—3 of Figure 2;

Figure 4 is a vertical transverse section taken also on the line 3—3 of Figure 2, but with the parts moved to a different position;

Figure 5 is a fragmentary horizontal section taken on the line 5—5 of Figure 4;

Figure 6 is a side elevation of one of the elements of the invention, and illustrating operating cam mechanism in section, taken on the line 6—6 of Figure 5;

Figure 7 is a side elevation of another cam operated element, the operating cam mechanism being shown in section, taken on the line 7—7 of Figure 5;

Figure 8 is a fragmentary horizontal section taken on the line 8—8 of Figure 3;

Figure 9 is a plan view of a modified form of the invention shown in the preceding figures;

Figure 10 is a fragmentary vertical section taken on the line 10—10 of Figure 9; and

Figure 11 is a fragmentary detail, to an enlarged scale, of clutch mechanism forming part of the modification shown in Figure 9.

As shown in Figures 1 to 8, inclusive, of the drawings, the invention comprises a substantially horizontal support 1, to which the crates C may be fed by any suitable roller or gravity conveyor, such as is commonly used for this purpose in bottling plants. When the crates are positioned on the support 1, they are moved transversely of an endless conveyor 2 by mechanism, the operation of which is controlled by the passage of a predetermined number of bottles to

a fixed position above the support 1. In other words, in the operation of this machine, the crates are fed intermittently to a predetermined position of rest on the support 1, such motion being controlled wholly by the movement of a predetermined number of bottles to a fixed position above the path of movement of the crates.

As shown clearly in Figures 1, 3 and 4 of the drawings, the upper branch 3 of the endless conveyor, moves substantially at right angles 10 to the direction of movement of the crates C on the support 1. The conveyor branch is moved across the support 1 by a power driven shaft 4 rotatably mounted in a journal bearing 5 which is suitably secured to a plate forming 15 part of the supporting framework of the machine. The shaft 4 has a bevel pinion 6 secured to the end thereof; and this pinion 6 meshes with a correspondingly beveled pinion 7, suitably secured to the end of a shaft 8 which is journaled 20 in bearing brackets 9 and 10, spaced apart along and suitably secured to a plate 11 forming part of the supporting framework of the machine.

A second shaft 12 is journaled at one end in a bearing 13 fixed to the plate 14 forming part of 25 the supporting framework of the machine. The other end of the shaft 12 extends into a clutch element 15 slidably mounted on and keyed to the shaft 8. The other clutch element 16 is fixed to the shaft 12 near the other end thereof 30 and is provided with a sawtoothed edge adapted to mesh with a correspondingly toothed edge on the clutch element 15. There is nothing novel in this clutch mechanism, which is merely illustrated here to show one form of a device by means 35 of which the normally non-rotating shaft 12 may be thrown into rotation automatically by the presence of a predetermined number of bottles on the upper branch 3 of the endless conveyor.

The clutch element 15 is provided with an annular groove 17 adapted to receive pins 18 and 19 extending inwardly toward each other from the furcations 20 and 21 of a shipper lever 22, which is secured to a vertical stub shaft 23 journaled in a bearing 24 fixed to the plate 11 of the 45 supporting framework. A crank arm 25 fixed to the lower end of the shaft 24, is pivoted at its other end to a rod 26 which extends across the support 1 to be pivotally connected to the end of a crank arm 27 secured to or formed integral 50 with a shaft 28, which is journaled in a bearing 29 fixed to the plate 14 forming part of the supporting framework.

A hook member 30 is secured to the end of the rod 26 near its pivotal connection to the 55 crank arm 27; and a tension spring 31 is detachably connected at one end to the end of the aforesaid hook member 30. The other end of the spring 31 is connected to a hook 32 at the end of a bolt 33, which projects slidably through an 60

aperture in a bracket 34 depending from the supporting plate 14. The outer end of the bolt 33 is screwthreaded to receive a nut 35 which impinges against the rear end of the bracket 34 and may be rotated to vary the tension of the spring 31 for the purpose of normally holding the shaft 28 in position to cause an arm 36 fixed to the end of shaft 28 to extend as a yielding stop member across the branch 3 of the 10 conveyor 2.

As shown in Figure 2 of the drawings, the clutch elements 15 and 16 have been moved, by the pressure of bottles against the arm 36, into engaged position in order to transmit the rotation of the shaft 8 to the shaft 12. It will be apparent from inspection of Figures 1 and 2 of the drawings that if there were no bottles on the conveyor 2 to rotate the arm 36 into the position shown in Figure 2, the tension of the spring 15 31 would pull the rod 26 and crank arm 35 so as to hold the shipper arm 32 in position to disengage the element 15 of the clutch from the element 16 and thereby release the shaft 12 from operative engagement with the power shaft 8.

25 The support 1 has secured to the opposite edges thereof the guide plates 37 and 38, serving to guide the crates C into proper position below a bottle guide frame 39 which is located immediately to the rear of the branch 3 of the conveyor 2. The bottle guide frame comprises the standards 40 and 41 suitably secured at their lower ends to the plates 37 and 38, respectively. A cross bar 42 connects the upper ends of the standards 40 and 41 and serves as a support for brackets 43 and 44 which rotatably support the pulleys 45 and 46, respectively.

40 A bottle guide 47 is mounted to slide vertically between the standards 40 and 41, which are provided with grooves 48 and 49, respectively, receiving the anti-friction rollers 50, rotatably mounted on opposite side walls of the bottle guide 47. Chains 51 and 52, suitably secured at one end to the top of the guide 47, extend, through apertures 53 and 54, respectively, in 45 the cross bar 42, and around the pulleys 45 and 46 to be secured to the upper ends of rocking arms 55 and 56.

45 The arms 55 and 56 are pivoted at their lower ends to the outer sides of the guide plates 37 and 38, respectively; and, near their lower ends are shaped to form enlargements 57 and 58, each of which is provided with a substantially rectangular slot 59 in which rotates a cam 60, fixed to the shaft 12. The arms 55 and 56 are similar 50 in every respect, their upper parts being bent from the plane of their lower parts to take care of the different distances of separation of the standards 40 and 41 and the guide walls 37 and 38.

60 A cross bar 61 extends between and is suitably secured to the arms 55 and 56. A pair of arms 62 and 63, pivoted to the cross bar 61, are fixed to the inner face of a push plate 64, which at its lower edge is slidably supported by the substantially horizontal flange 65 of an angle iron 66 suitably secured to the plate 14 which forms part of the framework of the machine, and which at its upper edge, constitutes one of the supports of the branch 3 of the endless conveyor. The 65 inlet end of the plate 64 has formed integral therewith a cut-off plate 67 forming a stop for the bottles B on the conveyor 2 whenever the push plate 64 is in the act of moving bottles from the conveyor into the bottle receiving recess of the bottle guide 47.

The shaft 12 is also provided with spaced apart cams 68 which operate in substantially rectangular slots 69 formed in arms 70 and 71 which are pivoted at their lower ends to lugs 70' and 71' extending downwardly from the guide plates 37 and 38, respectively. The upper ends of the arms 70 and 71 are pivoted to the ends of links 72 and 73 which have their other ends pivotally connected to swinging arms 74 and 75, which are pivoted at their upper ends to a cross bar 76 10 fixed to the standards 77 and 78. It will be noted that the arms 70 and 71 are provided with recesses 79, to clear the pivots connecting the lower ends of the arms 55 and 56 to the support plates 37 and 38. 15

The arms 74 and 75 are bifurcated at their lower ends, and these bifurcations are slotted to receive pins 80, which extend through bars 81 and 82, slidably mounted in brackets 83 and 84 secured to the inner faces of the guide plates 37 and 38. The opposite ends of each of the rods 81 and 82 are provided with lugs 85 and 86 pivoted at their upper ends to the sliding rod 81 and 82, and are provided with stop members 87 and 88 adapted to contact with corresponding 25 stop members 89 and 90 fixed to the sliding rods 81 and 82. It will be apparent from Figures 3 and 4 that the lugs 85 and 86 are capable of rotation only in an anticlockwise direction, as seen in these figures. Therefore, it will be obvious that 30 when the members 85 and 86 are in vertical position, they will be arranged within the partitions of the crates C so as to move the aforesaid crates forwardly under the conveyor 3 whenever the arms 70 and 71 are rocked about their lower 35 fulcrum pivots.

The cams 60 and 68 are so designed and arranged on the shaft 12 that while the crates are in a stationary bottle receiving position, the arms 55 and 56 have moved so as to lower the guide 40 47 onto the top of the partitions of the crate immediately below it. Before this lowering takes effect, the push plate 64 has moved a row of bottles into the spaces designed to receive them in the bottle guide 47. Immediately after the bottles have been pushed into these spaces, the bottle guide 47 begins its descent with the bottles therein to direct the aforesaid bottles into the spaces of the crate immediately below the aforesaid guide. The parts are so timed in operation 50 that while the crates are being moved forward by the lugs 85 and 86, the arms 55 and 56 are in retracted position to permit the bottles to be fed against a stop 91 which is suitably secured to the framework supporting the endless conveyor. 55

The solid guide 47 with its recesses presents decided advantages over the fixed guides of the prior art. This guide 47 slides vertically from the bottle receiving position directly onto the top of the partitions in the crates below, with the 60 bottle receiving recesses accurately registering with the compartments in the crates. If this guide were fixed in its upper position, the bottles moved into the recesses would be liable to move into the space below the lower edge of the guide 65 and the top of the crates and would probably cause a jamming of the mechanism and breakage of bottles. It is to eliminate the possibility of such jamming and breakage, that applicant's bottle guide has been mounted to slide from its 70 upper vertical bottle receiving position, as shown in Figure 3, to its lower bottle delivering position shown in Figure 4. By this construction, the guide 47 forms a positive means for delivering bottles of various sizes into the compartments 75

of the crate below. The necessity for the sliding construction of the guide 47 arises from the fact that the bottles extend beyond the top edges of the crate; and also because the crate moving members 81, 85, and 86 extend above the top edges of the crate and must have a clearance necessary for their proper operation.

In order to avoid mutilation of the sides of the crates C during their movement toward filling position, the guide wall 38 is provided with a series of antifriction rollers 92 which project through slots suitably formed in the wall 38 and are adapted to contact with one side of the crate C to facilitate their movement toward filling position. The other wall 37 is provided at suitable intervals with arms 93 pivoted at their outer ends to the wall 38 and extending through suitable slots therein toward the adjacent walls of the crates C. The free ends of the arms 93 are provided with rollers 94; and compression springs 95 are arranged between the wall 37 and the arms 93 so as to cause the rollers 94 to exert a yielding pressure on the crates C and force them against the rollers 92, thereby determining their positions laterally with respect to the bottle guide 47 and the bottle receiving recesses therein.

The form of the invention shown in Figures 9 and 10 is for the greater part quite similar to that illustrated in Figures 1 to 8, similar parts thereof being given the same reference numerals. In this particular form, the bottle guide 96 is fixed at its lower ends to the side walls 37' and 38' of the crate support. The clutch elements 15' and 16' are substantially the same as the corresponding elements shown in Figure 1 of the drawings. The shaft 8', however, does not extend across the crate supporting runway, but is turned down to form a shoulder 97 and a supporting extension 98, on which is rotatably mounted the clutch element 16'.

As shown clearly in Figure 11 of the drawings, the element 15' is keyed to the shaft 8'; while the element 16' is rotatably mounted on the shaft extension 98. The end of the extension 98 is screwthreaded to receive a washer plate 99 and a lock nut 100 to maintain the clutch element 16' against undue axial sliding movement on the extension 98.

The lower part of the clutch element 16' is provided with a crank arm 101 pivotally connected at its outer end to one end of the link 102, which at its other end is pivoted to an arm 103 extending from and forming one of the three arms of a lever, designated generally by the reference numeral 104, and pivoted at the junction of the arms 103, 105 and 106 to a shaft 107, which is rotatably mounted in bearings 108 and 109 suitably secured to a member 110 forming part of the conveyor supporting framework of the machine. The member 110 and a second member 111 correspond to the supporting members for the conveyor branch 3 shown in the other figures of the drawings.

The lower end of the arm 106 has pivotally connected thereto a pusher 112, adapted to ride over the upper edges of the partitions in the crate C and to extend into said partitions as shown in Figure 10 of the drawings, to move the crates step by step into bottle receiving position, under the bottle guide 96. A spring 113 secured to the arm 106 impinges against the upper edge

of the pusher 112, to force the latter into yielding contact with the upper edges of the partitions of the crate C.

As shown in Figure 9 of the drawings, there are two three-armed levers 104, secured in spaced 5 apart relation to the shaft 107. While one of these levers and the mechanism connected thereto would be sufficient to effect the necessary movements of the crate in properly timed relation toward the bottle receiver 96, it is preferable 10 to use two of these levers with the pushers connected thereto, in order to avoid any possibility of jamming the crates in their runways.

The pusher plate 110 is pivotally connected by the arms 114 and 115 to the upper ends of the 15 arms 105 of the three-armed levers, and leaf springs 116 secured to the edges of the arms 105 extend into contact with the inner face of the pusher plate 110, to hold the latter substantially in vertical position. A stop plate 117 is secured 20 to, or formed integral with, one end of the pusher plate 110, to prevent movement of bottles on the conveyor branch 3' while the pusher plate is in the act of moving the bottles into the recesses 25 formed in the bottle receiver 96.

It will be noted that the bottle receiver 96 extends downwardly to within a very short distance of the top of the crates supported by the runway 1. The rear wall in each recess of the bottle receiver is cut away as shown at 118, in 30 order to permit movement of the crates after insertion of the bottles therein.

It will be evident from inspection of Figure 10 of the drawings, that as the pusher plate 110 is moved inwardly to push the bottles into the recesses in the receiver, the pusher member 112 moves rearwardly over the upper edge of a partition in the crate, to engage the next rearward partition. The continued rotation of the shaft 107 rocks the arms 104 and causes movement of 40 the crates into bottle receiving position at the same time as they withdraw the pusher plate 110, to permit another group of bottles to be moved by the conveyor 3' against the stop member 91. 45

It is believed the operation of this form of the invention will also be apparent to persons skilled in the art, without further explanation, and from inspection of the drawings.

What I claim is:

Crating apparatus comprising a frame, a bottle guide reciprocable vertically on said frame and having a plurality of vertical bottle receiving recesses formed in one side thereof, a conveyor continuously moving bottles in a row in front of the recesses in said guide, means for intermittently moving crates under said conveyor to predetermined position below said guide, a pusher plate movable across said conveyor intermittently for pushing a predetermined number of bottles from said row into the recesses in said guide, means for operating said plate and crate moving means in alternation, mechanism operable by contact with a bottle on said conveyor for automatically controlling the operation of said operating means, and means connected to said pusher plate and operable during the movement of the plate toward said guide for lowering the guide onto a crate during the rest period thereof, and for raising said guide into bottle receiving position during the movement of said plate away from said guide. 50 55 60 65 70

CHARLES ALVIN MILLER, SR.
